CLAIM

The ornamental design for a soft camera case, substantially as shown and described.

DESCRIPTION

FIG. 1 is a front perspective view of the soft camera case.

FIG. 2 is a front view of the soft camera case.

FIG. 3 is a back view of the soft camera case.

FIG. 4 is a left view of the soft camera case.

FIG. 5 is a right view of the soft camera case.

FIG. 6 is a top view of the soft camera case; and,

FIG. 7 is a bottom view of the soft camera case.

The broken lines shown on the surface throughout the views symbolize a slide fastener.
